UNITED STATES PATENT OFFICE.

PURCELL THOMAS WEBB, OF CHRISTCHURCH, NEW ZEALAND.

HOLDER FOR FOUNTAIN PENS AND THE LIKE.

Application filed March 28, 1925, Serial No. 19,060, and in New Zealand September 9, 1924.

This invention relates to holders used for retaining fountain pens, pencils and the like in pockets of wearing apparel and has for its object the provision of improvements whereby such articles will be more securely guarded against loss by falling from the pockets than when known forms of holders are used.

The main improvement put forward by the invention consists in providing the holder with a spring clip adapted to grip the material at the outer side of a pocket said clip being caused to grip or to release said material as desired by the operation of a lever.

Other improvements are comprised in the form of the clip for gripping the material and in the combination with said clip of selected means for gripping pens, pencils and the like.

The drawing accompanying this specification, illustrates the various improvements, comprising the invention and the latter will be more particularly described in conjunction therewith.

Figure 1 being a perspective view and

Figure 2 a sectional elevation of one form of holder, the latter figure showing the spring clip closed, and

Figure 3 a sectional elevation of another form thereof while

Figures 4 and 5 are perspective views of further forms,

Figure 6 is an elevation and

Figure 7 a plan view of another form, while

Figure 8 is a perspective view, and

Figures 9 and 10 an elevation and a sectional elevation respectively of two still further forms.

Figures 11 and 12 are elevations showing modifications of the device illustrated in Figures 9 and 10.

Figure 13 is a perspective view of a still further form of the invention.

In the form shown in Figures 1 and 2 the holder comprises an inverted U shaped piece of metal 1, having integral therewith a pair of wings 2 approximately semi-circular in plan, and each being cut or stamped to provide inwardly projecting spring portions 2^a.

The portion 1 has fitted therein an inverted U shaped spring clip 3, the latter being provided with a projection 3^a cut and bent to enter a slot 4 in the portion 1, and so retain the spring clip in the latter.

The spring clip 3 has in one side a vertical slot 5, in which works a projection 7 on the bent end 6^a of a lever 6 pivoted across an opening 8 in the one side of the inverted U shaped portion 1.

The inside or facing surfaces of the spring clip 3 are provided with projections or spikes 9, for entering and holding the material to be gripped.

The holder shown in Figures 1 and 2 is secured in a pocket, by placing the wings 2 in the latter, and passing the spring clip 3 on to the upper edge of the material at the outer side or front of the pocket after which the lever 6 is moved to cause its inner end 6^a to force the slotted portion of the spring clip 3 towards the other portion thereof thereby causing said clip 3 to be compressed and to firmly grip the material of the pocket. When the lever 6 is moved to compress the clip 3, it is accommodated in the opening 8, the outer end of said lever extending beyond the inverted U shaped portion 1 or a recess being provided in the latter to facilitate the lever being gripped, when it is desired to operate said lever to allow the spring clip 3 to release its hold of the material of the pocket.

A pen, pencil or the like placed in the holder, between the wings 2, is gripped by the projections 2^a and securely retained in the pocket.

In the form shown in Figure 3 the spring clip 3 and the wings 2 are integral, the inverted U shaped portion 1 being placed over the spring clip 3, and retained thereon, by having a projection 10, bent and entered in a slot 10^a in said spring clip 3 or the latter may have projections to engage in recesses in the portion 1 the gripping of the pocket material by said clip 3 being performed in the same manner as previously described.

In the form shown in Figure 4 the inverted U shaped portion 1, spring clip 3 and lever 6 are constructed and operated as in the form shown in Figures 1 and 2, but the wings 2 instead of being formed

with pen or pencil gripping portions 2^a are provided with spaced spring extensions 11 contracted towards their ends and between which a pen, pencil or the like is forced and held thereby. The extensions 11 may also be provided on the wings 2 in the form shown in Figure 3.

The form of holder shown in Figure 5, comprises a tubular receptacle for a pen or pencil, integral with the inverted U shaped portion 1, said receptacle being in two portions 12, 13 which naturally tend to spring together so as to grip the pen or pencil.

Preferably the portion 12 of said receptacle extends above the portion 13 so as to facilitate the entrance of a pen or pencil into the receptacle while the inverted U shaped portion 1, is fitted with a spring clip 3, and lever 6, the same as in Figures 1 and 2. The latter form of holder also safeguards the pen or pencil held therein against breakage.

The form of holder shown in Figures 6 and 7 comprises an inverted U shaped portion 1, with a spring clip 3 and lever 6, as in Figures 1 and 2, said portion 1 being provided with inturned edges 14 adapted to grip and hold a member 15, to which is secured a pen or pencil gripping band 16 consisting of connected vertical loops of spring wire. In this last mentioned form the portion 1 may be of spring material and made to grip the pocket material.

The form of holder illustrated in Figure 8 consists of a tubular spring gripping receptacle 17 for a pen or pencil, said receptacle 17 having formed integral therewith at its upper end an inverted U shaped spring clip 18 from the back portion of which project lugs 19, the latter extending one at each side of the outer portion of the clip 18. A lever 20 with its inner end 20^a bent to approximately a right angle with the body portion, is pivoted between the lugs 19 so that by forcing said lever downwards, its bent end 20^a bears against the outer portion of the spring clip 18 and causes the latter to secure a firm grip of the pocket material on which it is placed. It will be obvious from the drawing that the holder 17 shown in Figure 8 could be provided with the pocket gripping means illustrated in Figure 5 and that the pocket gripping means of the device shown in Figure 8 could be used with the holder 12 shown in Figure 5.

Upon the lever 20 being moved upwards the spring clip 18 releases its grip of the pocket material and may be removed from same, and the pen or pencil gripping receptacle 17 withdrawn from the pocket.

In the form of holder shown in Figures 9 and 10 the inverted U shaped portion 1 is of spring material and has formed integral therewith or has attached thereto, any suitable form of pen or pencil gripping means

herein described, said member 1, having pivoted to the lower end of its outer leg, a lever 21, the inner end of which is formed with prongs 21^a, the centre portion of said inner end being bent to encircle a pin 22 secured to the lower end of the outer leg of the inverted U shaped portion 1, which is slotted at 23 to accommodate the central bent portion of the inner end of the lever 21.

The device with the lever 21 moved down as far as it will go, is placed so that the inverted U shaped portion 1 passes upon the upper edge of the material at the front of the pocket and so that the pen or pencil gripping means passes into the pocket as before. By then forcing the lever 21 upwards as far as it will go, the material in the portion 1 is gripped between the prongs 21^a and the back of the portion 1, and so secures the holder to the material at the front of the pocket, reverse movement of the lever 21 being given in order to release the grip of the material, and allow the holder to be removed.

In the form shown in Figure 11 the lever 21 is bent so that downward instead of upward movement is required to cause the material in the portion 1 to be gripped, and so that upward instead of downward movement, effects the release of said material.

The ends of the prongs 21^a in both of the forms shown in Figures 9 and 10 and Figure 11, are rolled or bent as at 24 to prevent injury to the material adapted to be gripped. It will also be obvious that the lever 21 could be used in other forms in place of the lever 6.

The lever 21 may also be used to operate a spring clip 3 (Figure 12) in a similar manner to the lever 6 shown in Figures 1 to 7 in which case the rolled portions 24 are not required.

The form of holder shown in Figure 13 is part tubular with a shield 26 between which and a spring member 27 attached to the tubular portion 25^a a pencil, pen or the like is adapted to be gripped. This form of holder may have attached thereto by riveting or otherwise or have formed integral therewith an inverted U shaped portion 1 in which is fitted an inverted U shaped spring clip 3 as before described, the latter being operated either by a lever such as 21, or by the before described lever 6.

What I do claim and desire to obtain by Letters Patent of the United States of America is:

1. A holder for pens, pencils and the like, comprising an inverted U-shaped member of spring metal formed integral with a tubular receptacle having spring portions adapted to receive and grip the pen, pencil or the like; and a lever pivotally mounted upon said holder and constructed so as to compress said inverted U-shaped member when actuated.

2. A holder for pens, pencils and the like comprising an inverted U shaped member of spring material formed integral with a tubular receptacle having spring portions adapted to receive and grip a pen, pencil or the like; lugs extending from the back portion of said inverted U shaped member, and

a lever with a bent end, pivoted between said lugs, for compressing said inverted U shaped member. ¹⁰

In testimony whereof I have signed my name to this specification.

PURCELL THOMAS WEBB.
